THERON I. SMITH, OF NORTH ATTLEBOROUGH, MASSACHUSETTS, ASSIGNOR
TO T. I. SMITH & CO., OF SAME PLACE.

DESIGN FOR A SHOE FOR COLLAR-BUTTONS.

SPECIFICATION forming part of Design No. 32,081, dated January 9, 1900.

Application filed December 13, 1899. Serial No. 740,226. Term of patent 7 years.

To all whom it may concern:

Be it known that I, THERON I. SMITH, a citizen of the United States, residing at North Attleborough, in the county of Bristol and State of Massachusetts, have invented and produced a new and original Design for a Shoe for Collar-Buttons, of which the following is a specification, reference being had to accompanying drawings, forming part thereof.

Figure 1 is a perspective view of my newly-designed shoe for collar-buttons. Fig. 2 is a top view, Fig. 3 an end view, and Fig. 4 a side view, of the same.

The leading feature of my design consists in the curved hook-shaped end of the shoe.

In the drawings, *a* indicates the post by which the shoe may be connected with a button; *b*, the gradually-narrowing plate of the shoe; *c*, convex heel portions of the shoe ex-

tending on each side of and beyond the surface of the post *a*, and *d* the curved-over narrow end of the plate of the shoe, resembling a hook. The post *a* is narrowest where it extends from the plate *b*, at a right angle to the surface of the same, and gradually increases in width to the end.

Having thus described my invention, what I claim as new, and desire to secure by Letters Patent, is—

The design for the shoe of a collar-button herein shown and described.

In testimony whereof I have signed my name to this specification in the presence of two subscribing witnesses.

THERON I. SMITH.
